[57] CLAIM

We claim the ornamental design for an enclosure for analytical instrumentation, as shown and described.

DESCRIPTION

FIG. 1 is an isometric view of an enclosure for analytical instrumentation showing our new design;
FIG. 2 is a top elevational view thereof;
FIG. 3 is a front elevational view thereof;
FIG. 4 is a left side elevational view thereof;
FIG. 5 is a right side elevational view thereof;
FIG. 6 is a rear elevational view thereof; and,
FIG. 7 is a bottom elevational view thereof.
